UNITED STATES PATENT OFFICE.

ROY STANLEY, OF CEDARVILLE, CALIFORNIA.

SCREEN-DOOR OPENER.

Application filed February 1, 1926. Serial No. 85,350.

This invention relates to screen-door opening devices, my principal object being to provide a structure for the purpose by means of which such doors may be readily opened by a person desiring to enter without the necessity of using his hands.

Since screen doors, which are commonly closed by the spring hinges without any catch means, are commonly used on residences for the back porch or kitchen, and through which tradesmen pass to deposit packages, of which their arms are frequently full, it will be evident that the application of my device to such doors will enable these persons to pass through the door and deposit their packages inside without having to lay such packages on the floor or elsewhere outside the door to permit them to use their hands to initially open the door, as is ordinarily necessary.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective outline of a screen-door showing my operating mechanism as applied thereto.

Fig. 2 is a side elevation of the mechanism showing the movement of the mechanism to open the door, in dotted lines.

Fig. 3 is a front elevation detached of the operating arm of the structure.

Referring now more particularly to the characters of reference on the drawings, the numeral 1 denotes a screen-door of ordinary character mounted in a frame 2 and held in place to the frame along one edge by the usual spring hinges 3.

My opening device comprises a vertical plate 4 secured onto the door a certain distance from the floor and adjacent the free edge of the door, this plate having an outwardly offset portion 5 overhanging the outer face of the adjacent frame 2. Fixed on the frame adjacent the bottom of the plate is a bearing sleeve 6 for a horizontal shaft 7 which is provided with a vertical arm 8. This arm extends upwardly to adjacent the

top of the member 5 and carries at its upper end a horizontal spindle 9 which projects between the member 5 and the frame 2.

A roller 9^a is mounted on this spindle to engage the face of the plate 5 nearest the frame. On the end of the shaft 7 opposite to the arm 8 and beyond the sleeve 6 is fixed another arm 10 preferably shorter than the arm 8 and projecting at an acute forward angle to the frame 2. This arm is arranged to be reversed on the shaft if necessary so as to enable the device to be mounted in connection with a right or left-hand opening door. An operating rod 11, connected at its upper end to the outer end of the arm 10, extends downwardly to a flexible connection with an eye 12 which is provided on the upper free end of a foot-pad 13. This pad is connected at its lower end with a hinge plate 14 secured on the floor 15 outside the door in suitable alinement with the opening structure.

A tension spring 16 secured at one end onto the frame 2 and at the other end onto the arm 10 or rod 11 at its upper ends, maintains the arms 10 and 8 and the pad 13 normally raised.

In operation a person desiring to enter the door presses sharply down on the pad 13 with a foot. This causes the arm 8 to descend, imparting a sudden outward movement to the plate 5 and door, such sudden movement being sufficient to cause the door to swing open a considerable distance. This enables the party desiring to enter to place his elbow or other part of the body against the inside of the door before the same tends to close, and thus allows the door to be further opened if necessary.

To prevent the roller 9^a striking against the frame 2 with the action of the spring 16, a rubber or other shock absorbing bumper 17 is mounted on said frame behind the arm 8.

I preferably enclose the main working parts (the arm 10, spring 16, bearing 6, etc.) in a housing as indicated at 18 in dotted lines on Fig. 2. This housing would be made of sheet metal or the like and besides keeping water and dirt away from these parts would add greatly to the neatness of appearance of the device.

It is also to be noted that while I have shown this device in connection with a door having coil spring hinges, it will of course work perfectly well with any of the devices

used in supporting screen doors and holding them closed.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention as defined by the appended claims.

Having thus described my invention what I claim as new and useful and desire to secure by Letters Patent is:

1. An opening mechanism for a hinged door comprising a rigid vertical member to be attached to the opening side of the door and to overhang the adjacent door frame, an upstanding operating arm whose upper end is adapted to engage the inner face of the overhanging portion of said member, a bearing member and support for the lower end of the arm adapted to be mounted onto said door frame, another and shorter arm mounted in axial connection with the operating arm and normally disposed at an upward diverging slope to the door frame, a foot pad structure comprising members hinged together, one of said members being adapted to be secured to the floor outside and to one side of the door and the other member normally projecting upwardly at an acute angle to the floor, and a flexibly connected link between the upper end of

said last named pad member and said short arm.

2. An opening mechanism for a hinged door comprising a rigid vertical member to be attached to the opening side of the door and to overhang the adjacent door frame, a normally vertical operating arm arranged at its upper end to engage said member, means pivotally mounting the lower end of the arm onto said door frame, a foot pad hinged onto the floor outside and to one side of the door and projecting upwardly at an acute angle to the floor, and connection means between said pad and the operating arm to cause the latter to swing outwardly with the depression of the pad.

3. An opening mechanism for a hinged door comprising a rigid vertical member to be attached to the opening side of the door and to overhang the adjacent door frame, a normally vertical operating arm arranged at its upper end to engage said member, means pivotally mounting the lower end of the arm onto said door frame, a foot pad hinged onto the floor outside and to one side of the door and projecting upwardly at an acute angle to the floor, and connection means between said pad and the operating arm to cause the latter to swing outwardly through a substantially ninety degree arc with a relatively small arcuate movement of the pad.

In testimony whereof I affix my signature.

ROY STANLEY.
